UNITED STATES PATENT OFFICE

MORIS HAAS, OF NEW YORK, N. Y.

BED-SPRING.

1,144,123.

Specification of Letters Patent. Patented June 22, 1915.

Application filed August 8, 1914. Serial No. 855,766.

To all whom it may concern:

Be it known that I, MORIS HAAS, a citizen of the United States, residing at the borough of Brooklyn, in the county of Kings, city and State of New York, have invented an Improvement in Bed-Springs, of which the following is a specification.

Heretofore, in the use of bed springs, as commonly constructed, the mattress is placed directly upon the top of the bed spring, and inasmuch as in the ordinary forms of bed springs no provision is made for preventing the mattress from spreading, the same will, in use, become flattened by the weight of the body lying upon the same, and will consequently spread at the sides, oftentimes becoming so flat and hard, eventually, as to be uncomfortable.

My present invention relates more particularly to upholstered box bed springs, and the object thereof is the provision of a box bed spring so constructed as to receive and yieldingly support a mattress and prevent the same from spreading, as will be herein-after more particularly described.

In the drawing, Figure 1 is a plan view of my improved box bed spring. Fig. 2 is a partial elevation and enlarged cross section on line 2, 2, Fig. 1. Fig. 3 is a perspective view showing the corner of a bedstead, and illustrating the use of my improved box bed spring in connection therewith, and Fig. 4 is a partial cross section illustrating the manner in which the cover and the lining are connected together, and both these parts secured in position relatively to the frame.

In constructing my improved box bed spring, I preferably employ a base made of rails 10 and 11, suitably secured to one another at right angles. I also preferably employ depending flange rails 12, suitably secured to the rails 11, and adapted to fit within the head and side rails of the bedstead, to maintain the bed box spring in position therein. In suitably spaced positions, and connected at one end to the rails 10, are springs 13. As illustrated, these springs are double volute springs, and at their inner or lower ends, are secured to the rails 10 by staples 14. It will be understood, however, that any suitably shaped springs may be employed, and the same may be connected to the rails in any desired manner. Also, as is customary in bed springs employing the type of spring illustrated in the drawing, these springs are

suitably connected or tied together by cross straps 15. I also employ a rim 16, which may be made of light wood, metal or other similar material, and which is preferably rectangular to define the upper outline of the box bed spring. Associated with the rim 16 is an auxiliary rim 17, of the same configuration but appreciably smaller dimensions, both rectilinear and in cross section. The auxiliary rail 17 is preferably made of a sufficiently heavy wire to answer its purpose.

In carrying out my invention, the upper or outer end of each of the outer or marginal springs 13 is preferably formed in the shape of a U 18 and bent at an inclination, so that the parallel portions thereof extend between the auxiliary rims 17 and main rim 16. Adjacent its spring, each U-shaped end thereof is secured to the auxiliary rim 17 by a suitable tie, as indicated at 19, while the base of the U-shaped end is secured to the main rim 16 by suitable ties indicated at 20. At its extremity, the U-shaped end of each spring is formed in an eye 21 to engage the upper portion of the next adjacent spring. At the corners I also prefer to employ connecting members, indicated at 22, extending between the main rim 16 and the auxiliary rim 17, to both of which these members are suitably connected and also to the adjacent spring 13 by a tie, as indicated at 23.

The structure, as hereinbefore described, is provided with a cover 24 made of a suitable fabric, which extends under the base, along the sides and over the main rim 16 and is suitably connected to the auxiliary rim 17. Secured to the cover 24, and also to the auxiliary rim, is a lining 25, which fits within the frame made of the said rims and the connecting portions of the springs, and upon which the mattress rests when in position, it being understood that the frame is so formed as to receive the mattress 26 with its edges in contact with the parts of the frame so as to prevent the same from spreading.

By referring to Fig. 4, it will be seen that the outer edge of the cover 24 is carried over the rim 16 and the auxiliary rim 17, and the edge thereof turned up against the then inner surface of the cover, while the outer portions of the lining 25 are carried beneath the auxiliary rim 17 and the edge portions thereof, together with the then adjacent portions of the cover 24, are secured

together and to the adjacent part of the cover 24 by a line of sewing 27, or otherwise.

By reference to Fig. 3, it will be seen that the base may be so constructed that the flange rails 12 depend therefrom as to fit within the rails 28 and 29 of the bedstead, one corner post of which is illustrated, at 27. It will be further understood that the box bed spring, as hereinbefore described, 10 may be employed in couches, and other similar structures, by, for example, suitably fitting the depending flange rails 12 with sockets or other devices for receiving rollers or casters, and that irrespective of the use to 15 which the box bed spring is put, it is designed to prevent the mattress, employed therewith, from spreading.

I claim as my invention:

1. A box bed spring comprising a base, a 20 rim defining the outline of the upper portion of the box bed spring, an auxiliary rim of similar configuration but smaller than the said rim and lying between the same and the said base, a plurality of springs, each secured at one end to the said base, the opposite ends of the outer springs being formed in the shape of inverted U's, means for securing a portion of the said outer springs to the said auxiliary rim, and means for 25 securing the base of the said U-shaped portions of the said outer springs to the said rim, the said rim, auxiliary rim, and those portions of the said springs extending be-

tween the same, forming a frame to receive a mattress so as to prevent the same from 35 spreading.

2. A box bed spring comprising a base, a rim defining the outline of the upper portion of the box bed spring, an auxiliary rim of similar configuration but smaller than the 40 said rim, and lying between the same and the said base, a plurality of springs, each secured at one end to the said base, the opposite ends of the outer springs being formed in the shape of inverted U's, ties for 45 securing a portion of the said outer springs to the said auxiliary rim, means for securing the base of the said U-shaped portions of the said outer springs to the said rim, a cover extending between the said base and 50 rim and secured to the said auxiliary rim and a lining secured to the said cover adjacent the said auxiliary rim, the said rim, auxiliary rim, and those portions of the 55 said springs extending between the same, together with that portion of the cover extending between the said rim and the auxiliary rim and also the lining, forming a receptacle for a mattress to prevent the same from spreading.

Signed by me this 5th day of August, 1914.

MORIS HAAS. [L.s.]
